UNITED STATES PATENT OFFICE.

EDWARD B. ALLEN, OF BRIDGEPORT, CONNECTICUT, ASSIGNOR TO THE SINGER MANUFACTURING COMPANY, A CORPORATION OF NEW JERSEY.

GIMP-THREAD-PULL-OFF DEVICE FOR BUTTONHOLE-SEWING MACHINES.

1,278,817.

Specification of Letters Patent. Patented Sept. 17, 1918.

Application filed August 10, 1917. Serial No. 185,409.

To all whom it may concern:

Be it known that I, EDWARD B. ALLEN, a citizen of the United States, residing at Bridgeport, in the county of Fairfield and

5 State of Connecticut, have invented certain new and useful Improvements in Gimp-Thread-Pull-Off Devices for Buttonhole-Sewing Machines, of which the following is a specification, reference being had therein 10 to the accompanying drawings.

This invention relates particularly to buttonhole sewing machines having gimp-thread guiding means adapted to lay a gimp-thread about a buttonhole as it is being 15 stitched. The gimp-thread, in accordance with the customary practice, runs from a supply-spool or cop stationed at the base of a spool-stand in rear of the machine and extends over an elevated guide carried by 20 said spool-stand and thence downwardly and forwardly through suitable guides at the side of the machine-frame and, laterally, into said frame in proximity to the lower elements of the stitch-forming mechanism. Within 25 the machine-frame a gimp-thread usually traverses a more or less tortuous course through suitable guides in its passage up to the apertured throat-plate or "button" which guides the thread within the range of action 30 of the stitch-forming mechanism.

It has been found that the slight drag often imposed upon the gimp-thread by the supply spool as the thread is being unwound from the latter, greatly retards the free passage 35 of the gimp-thread through the guides on the machine, and causes said guides to impose an excessive drag or friction upon the gimp-thread so that it can only with great difficulty be pulled through the guide 40 at the stitching point. This excessive drag on the gimp-thread is particularly undesirable as it results in imperfections in the finished buttonhole, such as a reduction in the size of the eyelet-end or other distortion of 45 the normal shape of the buttonhole. Also, when the work is shifted to a new stitching position, the previously stitched buttonhole must resist the pull exerted on the gimp-thread to draw it through its guide at the 50 stitching point. Excessive friction or drag on the gimp-thread at this time results in further distortion of or injury to the buttonhole.

Heretofore, to obviate these difficulties, it 55 has been customary for the operator to catch

the gimp-thread at the rear of the machine, between stitching operations, and pull a small quantity of the thread from the supply. This action by the operator, however, is tiring and results in the loss of much 60 time, causing a reduction in the amount of work produced by the machine.

The present invention, therefore, has for an object to provide automatic means for pulling off gimp-thread from the supply-spool or cop and freely supplying the required amount of slack gimp-thread to the machine during stitching and work-shifting operations, so that no abnormal or excessive drag will be imposed upon the gimp-thread 70 as it is drawn through the guide-button or throat-plate.

To this end I have provided a buttonhole sewing machine with a gimp-thread measuring or pull-off device comprising relatively 75 movable gimp-thread engaging devices and have provided actuating means therefor controlled by a moving part of the machine, so that the operator thereof is entirely relieved of the necessity of attending to the slackening 80 of the gimp-thread.

In the accompanying drawings, Figure 1 illustrates the base-portion of a buttonhole machine of a well-known type embodying the present invention. Fig. 2 is a rear end-elevation of a portion of the machine-frame showing the pull-off applied thereto. Fig. 3 is a perspective view of the pull-off guide-bracket. Fig. 4 is a perspective view showing the course of the gimp-thread adjacent 90 the stitching point.

In the present instance, the invention is embodied in a sewing machine of the type adapted to stitch buttonholes in leather as more fully represented in my Patent No. 95 1,048,786, dated December 31, 1912, and in the application of E. B. Allen and B. F. Crosby Serial No. 106,761, filed June 30, 1916. The machine frame is formed with a hollow base 1 from which rises a standard 100 2 supporting the usual superstructure including the reciprocating needle 3, which co-operates with lower stitch-forming means of any desired type such, for example, as represented in said Allen and Crosby application, disclosing the lower curved needle 4. The machine is equipped with the usual buttonhole cutting mechanism including the traveling fulcrum block 5 for the cutter levers 5^a and 5^b which block and cutter- 105 110

levers are actuated in the usual manner by the cutter-shaft 6. The machine further includes the customary traveling work-holder or carrier including the usual work clamp-
5 ing and supporting elements 7^a and 7^b, respectively, and is provided with the usual stop-mechanism 8, all as more fully represented in the said patent and application above referred to. As is well known, ma-
10 chines of this type are usually provided with automatic means for imparting a single rotation to the cutter-shaft to effect the cutting of the buttonhole slit whereupon the stitch-forming mechanism is automatically
15 thrown into operation to overseam the cut edges of said slit.

The present improvement, in its preferred embodiment, comprises a crank-disk 9 secured to an out-board projection of the cutter-shaft 6 and carrying a crank-pin 10 which is embraced by the apertured upper end of a pull-off rod 11 whose lower end-
20 portion is slidably received within an aperture or slideway 12 in the guide-bracket 13 secured to the base 1 by screws 14 and is formed with a thread-eye 15. The guide-
25 bracket is formed at opposite sides of the pull-off rod with side-wall portions apertured at 16, 16 to guide the gimp-thread to
30 and away from the thread-eye 15. As will be apparent, the relatively movable thread-
guides 15 and 16 coöperate to pull off gimp-
35 thread from the usual supply-spool stand (not shown).

35 In the particular embodiment of the invention illustrated, the gimp leads forwardly from the pull-off to a light tension-
device 17 and through an aperture 18 in the side wall of the base 1. Within the base 1
40 the gimp-thread may lead through a guide 19, thence upwardly through the guide tube 20, thence through the guide aperture 21 in the supporting shank 22 of the usual throat-
45 plate or "button" 23 and through the guid-
ing and needle clearance aperture 24 in said throat-plate which delivers the gimp-thread within the range of action of the stitch-
forming mechanism.

The starting of the machine effects a single
50 complete rotation of the cutter-shaft 6 which moves the rod 11 down and up, thereby pulling or measuring a bight *b* of gimp-
thread from the supply *s*. As the stitch-
forming mechanism is stationary at this time
55 any backward pull upon the gimp-thread by the pull-off will have no ill effect. The supply of slack thread *b* afforded by the
pull-off at the side of the machine will be sufficient for a buttonhole-stitching or a
60 work-shifting operation, or both, and will completely overcome the heretofore excessive drag imposed upon the gimp-thread when the operator fails, for any reason, to provide slack gimp-thread between the supply
65 spool and the machine.

The effective stroke of the pull-off implement is made sufficient to provide a quantity of slack thread somewhat in excess of the amount required for the longest buttonhole to be stitched plus the amount required for 70 a maximum shift of the work between stitching operations. If this maximum quantity of slack gimp-thread is not all used up, the remainder will be absorbed during the first part of the succeeding stroke of the pull-off, 75 as will be readily understood.

It is to be understood that the invention is equally well adapted for application to a buttonhole machine in which the cutter is actuated at the close of the stitching cycle. 80 In such case the gimp-thread pulled off at the close of a cycle of operations is available for the shifting of the work and the stitching of the next buttonhole. It is to be further understood that while the pull-off, as disclosed, is actuated by a cutter-shaft, it may be actuated by various other moving parts of the machine, within the scope of the invention. While the invention is disclosed in connection with a buttonhole sewing ma- 90 chine, it is obvious that the improvement is well adapted for use in other types of pattern stitching machines having certain characteristics of a buttonhole sewing machine such as covering stitch-forming mechanism 95 of one form or another and a guide for delivering a filler or other thread to be covered to a point within the range of action of the covering stitch-forming mechanism.

Having thus set forth the nature of the 100 invention, what I claim herein is:—

1. In a sewing machine, in combination, overseaming stitch-forming mechanism, a stop-motion for controlling the period of operation of said stitch-forming mechanism; 105 work-supporting means, a guide adapted to deliver a thread to be covered to a point within the range of action of said overseaming stitch-forming mechanism, and means adapted to act on the thread to be covered 110 between the source of supply and said guide to pull said thread from the supply and thereby afford a supply of slack thread throughout substantially the entire stitching period. 115

2. In a sewing machine, in combination, overseaming stitch-forming mechanism, a throat-plate, a guide substantially fixed relatively to said throat-plate and adapted to deliver a cord to be covered to a point within 120 the range of action of said overseaming stitch-forming mechanism, and means adapted to act upon said cord between said guide and the source of supply to pull said cord from the supply and thereby afford slack 125 cord for the ensuing stitching operation.

3. In a buttonhole sewing machine, in combination, stitch-forming mechanism, work-supporting means, buttonhole cutting mechanism, a gimp-thread guide adapted to 130

- deliver gimp-thread to the stitching point within the range of action of said stitch-forming mechanism, and a gimp-thread pull-off including relatively movable thread-engaging devices adapted to engage the gimp-thread between said gimp-thread-guide and the supply, and an operative connection between a moving part of the machine and at least one of said devices, whereby a free supply of slack gimp-thread is available during stitching or work-shifting operations.
4. In a buttonhole sewing machine, in combination, stitch-forming mechanism, work-supporting means, a gimp-thread guide adapted to deliver gimp-thread to the stitching point within the range of action of said stitch-forming mechanism, and an automatic gimp-thread pull-off device adapted to engage the gimp-thread between said gimp-thread-guide and the source of supply.
5. In a buttonhole sewing machine, in combination, stitch-forming mechanism, work-supporting means, buttonhole cutting mechanism, a gimp-thread guide adapted to deliver gimp-thread to the stitching point within the range of action of said stitch-forming mechanism, and means controlled by the action of the machine and engaging the gimp-thread between said gimp-thread guide and the supply for measuring off enough gimp-thread for the next stitching operation.
6. In a buttonhole sewing machine, in combination, stitch-forming mechanism, work-supporting means, buttonhole cutting mechanism, a gimp-thread guide adapted to deliver gimp-thread to the stitching point within the range of action of said stitch-forming mechanism, and means controlled by the action of said cutting mechanism for measuring off gimp-thread from the supply.
7. In a buttonhole sewing machine, in combination, stitch-forming mechanism, work-supporting means, buttonhole cutting mechanism including a cutter-shaft making a single rotation during each buttonhole producing cycle, a gimp-thread guide adapted to deliver gimp-thread to the stitching point within the range of action of said stitch-forming mechanism, and a gimp-thread pull-off device operatively connected to said cutter-shaft.
8. In a buttonhole sewing machine, in combination, a cutter-shaft, a crank carried thereby, a gimp-thread pull-off bar apertured at one end and at its opposite end connected to said crank, and a guide member coöperating with said pull-off bar.
9. In a buttonhole sewing machine, in combination, a cutter-shaft, a guide-member formed with a guideway, and a pull-off implement fitted to slide in said guideway and connected with said cutter-shaft.
10. In a buttonhole sewing machine, in combination, stitch-forming mechanism, button-hole cutting mechanism including a cutter-shaft, and a gimp-thread pull-off implement deriving motion from said cutter-shaft.

In testimony whereof, I have signed my name to this specification.

EDWARD B. ALLEN.
